UNITED STATES PATENT OFFICE.

THOMAS J. NEWLYN, OF EL PASO, TEXAS.

COSMETIC LOTION.

1,408,384.

Specification of Letters Patent. Patented Feb. 28, 1922.

No Drawing.

Application filed June 21, 1920. Serial No. 390,472.

To all whom it may concern:

Be it known that I, THOMAS J. NEWLYN, a citizen of the United States, residing at El Paso, in the county of El Paso and State 5 of Texas, have invented certain new and useful Improvements in Cosmetic Lotions, of which the following is a specification.

This invention relates to the treatment of the skin for the purpose of removing certain 10 imperfections from the epidermis and improving the appearance.

Owing to its exposure, the skin is particularly liable to the injurious effects of heat and cold and to injury from various causes 15 both external and internal. Prolonged exposure to the sun or electric light has a caustic action, as in "sunburn." Undue friction or pressure from the clothing may cause a chafed and sometimes an inflammatory condition.

The object of my invention is to provide a compound or lotion which may be applied to the skin without any danger of producing an injurious effect and which will act 25 upon the epidermis or scarf-skin to cause it to slough and yet will not penetrate too deeply in any manner to injure the corium or true skin.

My lotion for the treatment of the skin 30 may be compounded for ordinary conditions in the following proportions, viz:—

Resorcin	17%
Glycerin	13%
Alcohol	45%
Water	25%

To each fluid ounce of the compound I add two drops of carmin solution.

The effect produced by the several 40 ingredients upon the skin and the manner in which they coact and modify each other when combined is as follows:—The glycerin rapidly absorbs the water and moisture from the tissues and causes the outer skin to be 45 come dry and anhydrous. While this action is taking place, the resorcin acts as an escharotic which results in the exfoliation and sloughing of the epidermis or scarf-skin. Resorcin, though useful in certain subacute 50 or chronic skin affections, when used alone it is somewhat irritating, acting as a rubifacient and producing an itching but by combining it with glycerin which acts as an emollient, the more viscous action of the 55 resorcin is checked and nullified. The glycerin is compatible with the resorcin and

both are freely miscible with the alcohol and water of the formula. The glycerin acts also to separate the layers of the skin after the manner of a lamination and would of 60 itself "peel" slightly in a soft shreddy manner. The combined action of the glycerin and resorcin causes the epidermis or scarf skin to aschar and become dry in from three to six days, when it may be peeled off in 65 strips. The alcohol not only dissolves the resorcin and holds the glycerin and resorcin in solution in the compound, but it also causes the solution to spread freely when applied and increases the rapidity and depth 70 of penetration. The function of the water is to weaken the solution to the proper strength to eliminate any burning tendency and to further accentuate or enhance the emollient effect of the solution as a whole. The glycerine also weakens the solution and counteracts as an emollient. In other words, the alcohol, resorcin and glycerin are so proportioned as to avoid any heating or irritating 75 action upon the skin. The carmin or red 80 coloring is added to prevent the actinic rays of light from acting upon the resorcin in a manner to discolor the solution as well as to enhance the aesthetic effect.

The solution is applied to the skin of the 85 face, neck, breast or arms by means of a soft cloth, absorbent cotton, or other suitable means, preferably four times a day for a period of from three to five days according to the part to which it is applied, the arms 90 requiring a longer period than the face. By allowing two or three days to elapse after the final application or period, nature assists in drying the now dead coat of the outer layer of the epidermis and it begins to 95 peel and curl up. It may then be taken off in strips. Beneath will be found a fresh new skin.

It is sometimes desirable to repeat the operation for the purpose of removing a 100 second and even a third layer.

The rapidity and intensity of action may be varied and controlled by changing the proportions of the several ingredients in the compound in the proper proportion. By increasing the amount of resorcin the rapidity of action is increased but this must be accompanied by a reduction in the amount of glycerine together with a proportionate change in the quantity of alcohol and water. 110

The proportions may also be varied to accommodate the compound to different con-

ditions. In cases wherein heavy tissue of the scarf skin is to be sloughed, as on arms, long exposed to the sun and the elements and which is therefore more hardened the 5 escharment may be enhanced by using a larger proportion of resorcin. Inasmuch as the glycerine is weakened, the alcohol may also be decreased. On the other hand when the resorcin is decreased and the glycerine 10 is increased, more alcohol is required to cause the penetration and consequent absorption of the glycerine which otherwise would lie upon the surface of the skin. It will be apparent, therefore, that I may control the effect of the compound by properly 15 varying the proportions of the ingredients of the compound and produce a "sliding-scale action" upon the scarf-skin and a quickened or a retarded period of sloughing 20 and exfoliation of the skin. The relative proportions of the ingredients to produce the "sliding-scale action" of the compound are substantially as follows:—

Resorcin	12	13	14	15	16	17	18	19	20	21	22
Glycerin	18	17	16	15	14	13	12	11	10	9	8
Alcohol	50	49	48	47	46	45	44	43	42	41	40
Water	20	21	22	23	24	25	26	27	28	29	30

While the above proportions produce the best results, it is possible to obtain fairly good results with slight variations therefrom.

While others have heretofore employed preparations which caused the skin to scale, I believe I am the first to provide a compound which causes the separation of the

outer layer of the epidermis to laminate or separate en masse so that it may be taken off in actual strips. I have taken advantage of the fact that the skin is constantly renewing itself and so act upon the skin that a full opportunity is given to the skin to renew the under layer while it is still provided with an outer protecting sheath or cover.

I claim:—

1. A liquid compound for causing the outer skin to peel or slough off, comprising resorcin, glycerine, alcohol and water, the resorcin being sufficient to produce an escharotic action upon the outer layer of the epidermis, glycerine sufficient to prevent any irritating or burning effect of the resorcin and alcohol and water amounting together to substantially 70% of the mixture.

2. A liquid compound for causing the outer skin to peel or slough off, comprising resorcin in quantity from 12 to 22%, glycerine varying in inverse proportion thereto from 18 to 8%, alcohol in inverse proportion from 50 to 40% and water varying from 20 to 30%.

3. A liquid compound for causing the outer skin to peel or slough off, comprising resorcin in quantity from 12 to 22%, glycerine varying in inverse proportion thereto, and alcohol and water together constituting 70% of the mixture.

In testimony whereof I affix my signature.

THOMAS J. NEWLYN.
